4 Sheets-Sheet 4

A technical drawing of a mechanical assembly, likely a gear or sprocket. The drawing shows a central horizontal shaft with a gear attached. A rectangular housing or frame is positioned above the shaft. Various dimensions are indicated: 76' and 74 are on the left side; 69 is on the top left; 271 is on the bottom left; 81 is at the top right; 83 is above 81; 82 is to the left of 83; 25 is below 82; and 195 is on the far right.

UNITED STATES PATENT OFFICE.

ALBERT P. BALL, OF ROYAL OAK, MICHIGAN, ASSIGNOR TO SQUARE D COMPANY, OF DETROIT, MICHIGAN, A CORPORATION OF MICHIGAN.

ELECTRIC SWITCH.

Application filed May 1, 1919. Serial No. 293,936.

To all whom it may concern:

Be it known that I, ALBERT P. BALL, a citizen of the United States, residing at Royal Oak, in the county of Wayne and 5 State of Michigan, have invented certain new and useful Improvements in Electric Switches, of which the following is a full, clear, and concise description thereof.

My invention relates to electric switches 10 which may be manually or automatically operated and of the enclosed type or of the open type.

It is an object of my invention to provide such a switch which will always have a quick 15 break whenever the connection between the contacts is ruptured. Such a break will minimize the burning of the contacts by arcing.

Another object of my invention is to provide 20 a switch in which complete closure of the switch contacts must be effected before the force operating to close the switch is removed, else the switch contacts will be automatically opened. This will prevent leaving 25 the switch incompletely closed with consequent high contact resistance followed by heating or burning of the contacts.

Another object of my invention is to co-operate in a single structure both the above 30 desirable features and to thereby produce a positive make quick break switch which may be readily used alone and associated with fuses and enclosures.

Other objects of my invention appear in 35 reading the following specification along with the drawings.

In the drawings, I have shown three embodiments of my invention, each of these embodiments comprising a multi-blade 40 switch of knife blade type enclosed in a suitable housing and provided with means to insure that the switch contacts are completely closed when the force is removed from the operating handle. While these embodiments are applied to knife blade switches, it 45 is apparent that the invention is not limited to switches of the knife blade type, but that the invention is broad and may be applied to switches of other than the knife blade type. I, therefore, desire that the drawings 50 shall be considered merely as illustrative and not in a limiting sense, and that my inven-

tion shall be limited solely by the claims which follow this specification.

In the drawings—

Fig. 1 is an elevational view of one embodiment of my invention, the switch contacts being shown in open position, and the cover of the switch box opened to disclose the interior.

Fig. 2 is a section on the line 2—2 of Fig. 1 with the contacts in the same relative position.

Fig. 3 is a perspective view of the switch and associated parts shown in Fig. 1, the 65 switch being in closed position.

Fig. 4 is a diagrammatic illustration showing the relation of parts as the operating crank moves the switch contacts toward the closed position, such relation being assumed when the crank is moved from the position shown in Fig. 2.

Fig. 5 shows the parts shown in Fig. 4 with the switch blades almost completely closed.

Fig. 6 shows the relation of these parts when the operating crank has been moved to condition the switch for opening.

Fig. 7 is a second embodiment of my invention, the switch contacts being shown in 80 open position and the cover of the switch box opened to disclose the interior.

Fig. 8 is a section on the line 8—8 of Fig. 7 with the contacts in the same relative position.

Fig. 9 is a perspective view of the switch and associated parts shown in Fig. 7, the switch being in closed position.

Fig. 10 is a diagrammatic illustration showing the relation of parts as the operating crank moves the switch contacts toward the closed position, such relation being assumed when the crank is moved from the position shown in Fig. 8.

Fig. 11 shows the parts shown in Fig. 10 with the switch blades almost completely closed.

Fig. 12 shows the relation of these parts when the operating crank has been moved to condition the switch for opening.

Fig. 13 is a third embodiment of my invention, the switch contacts being shown in open position and the cover of the switch box opened to disclose the interior.

Fig. 14 is a section on the line 14—14 of Fig. 13 with the contacts in the same relative position.

Fig. 15 is a sectional view on the line 5 14—14 of Fig. 13 showing the switch closed.

Fig. 16 is a diagrammatic illustration showing the relation of parts as the operating crank moves the switch contacts toward the closed position, such relation being assumed when the crank is moved from the 10 position shown in Fig. 14.

Fig. 17 shows the parts shown in Fig. 16 with the switch blades almost completely closed.

Fig. 18 shows the relation of these parts 15 when the operating crank has been moved to condition the switch for opening, and

Fig. 19 is a perspective view showing a 20 three bladed switch associated with my improved means to insure the switch contacts being completely closed.

Reference is now made to Figs. 1 to 6 of the drawings showing one embodiment of my invention and in which similar reference characters indicate the same parts through the several views. I have mounted 25 in an armorclad switch box 20 with a cover 21 an insulating base 22. This base, in the form shown, is adapted to carry a two pole switch and has fuse contacts 23, fixed 30 blade receiving jaws 24 and fixed pivot posts 25. Mounted in the side walls 26 of the switch casing 20 is an operating crank 27 having an exterior handle 28. This 35 crank interior of the box is of bail or U-shaped configuration and is generally mounted with its axis approximately in line with the pivot posts 25. Pivoted on the posts 25 are the movable contacts 29 which 40 are adapted to bridge from the posts 25 to the fixed contacts 24. Beneath each of the pivot posts 25 and fastened to the insulating base 22 by the same screws, or other devices, as are used to hold the posts 25 in 45 position, I have placed a substantially flat anchorage 30 of sheet metal. This piece of metal extends outwardly, as shown in Fig. 3, being provided with outwardly and upwardly extending prongs 31. A coil spring 32 is held in position by being placed under these prongs 31. This spring is also placed under the knife blade 29 and reacts 50 against the knife blade some distance removed from the axis of the pivot posts. 55 These springs 32 are for the purpose of urging the switch blade 29 away from the fixed contact 24, thereby providing a switch which is always biased toward the open position. This spring and support I find to be a very 60 convenient arrangement for accomplishing the purpose, as it may be incorporated in the structures of the existing type with practically no change other than the mere assembly of parts as no re-arrangement is necessary.

Intermediate the switch blades 29 and on the insulating base 22, I have mounted a retaining device which is adapted to cooperate with parts to be described in order to retain the switch blades in closed position 70 against the biasing of contacts by the spring 32. This retaining device in the form here shown comprises a small housing member 33 formed of a single piece of sheet metal by bending upwardly two opposite walls 34 75 and folding the ends 35 of those walls at right angles thereto. Each of the walls 34 is provided with a hole 36, and in this hole I have loosely mounted an element 37, this element having a hole or opening 38 which 80 is made by striking out a projection 39. A spring 40 is fastened in any suitable fashion to the housing 33 and is engaged with the projection 39 to bias the element 37 against the inwardly bent ends 35.

Each of the blade contacts 29 has associated therewith a connecting device 41, one portion of which is adapted to be fastened tightly to the blade and another portion 42 of which is adapted to clamp a crossarm in 90 position. These clamps, of which there is one for each blade, are arranged intermediate the ends of the blade. The crossarm comprises a metal rod 43 which is long enough to extend across all the blades. This 95 rod or crossarm 43 carries insulating sleeves 44 which are clamped into position by the clamps 42, whereby the switch contacts may be operated in unison and are insulated from one another.

Intermediate the sleeves 44, I have mounted two washers 45 and intermediate these washers a link 46 is pivoted to the metal rod 43, one end of this link being provided with an elongated slot 47, the operating crank 27 being passed through the slot 47. The other end of the link 46 has a hook-like configuration, and in the form shown this hook has a sloping surface 48 which is adapted to move the element 37 100 against the action of the spring 40 as the switch is moved toward the closed position, as for example, as shown in Fig. 5. This hook-like end also has such configuration 105 that the element 37 may be passed by the point 49 of the hook and retain the hook 110 in the position shown in Fig. 3.

The cover 21 is provided with an L-shaped member 50 which is adapted, when the cover 120 is in closed position, to limit the opening movement of the switch crank 27, and to thereby prevent the crank and movable switch parts from moving too far in the open direction. One side wall 26 of the box 125 is provided with an angle iron projection 51 which is adapted to limit the extreme opening movement of the switch operating crank when the cover is opened. The switch may be locked in the open position by moving the crank 27 into engagement with the pro- 130

jection 51 and closing the cover, whereupon the L-shaped element 50 will overlie the switch crank 27 thereby preventing closing of the switch.

5 The operation of my improved switch structure will now be described. Considering first that the switch is in open position, as shown in Fig. 2, and that it is desired to close the switch, the operating handle 28 10 is moved in a clockwise direction from the position shown in Fig. 2 to that shown in Fig. 4. During this movement the switch contacts will remain in the same relative position as before for the crank 27 will traverse the length of the slot 47 in the link 46. The link 46 will, however, be oscillated upon the crossarm 43 as a pivot. When, however, the crank 27 has traversed the entire length 15 of the slot 47 further movement of the handle in the direction of the arrow in Fig. 4 will move the switch contacts toward the closed position. About the same time that the contacts first engage, the sloping surface 48 on the lower end of the link 46 will 20 engage the upper end of the element 37. Further movement of the crank will force the switch blades home and will swing the element 37 on its pivot 36 against the action of the small biasing spring 40 to the 25 position shown in Fig. 5. The operating means, however, must be moved a little further, for were the hand now to be removed from the crank 28, the springs 32 would throw the switch blades to open position. 30 If, however, the pressure from the operating crank is continued the link 46 will have moved so far, that the spring 40 may throw the element 37 to the position shown in Fig. 3 when the hook 49 will have engaged with the hole 38. In this position the spring 32 35 cannot act to open the switch as the switch is positively retained closed by the engagement of the hook 49 with the retaining device. When it is desired to open the switch 40 the switch crank 27 is moved counterclockwise, or in the direction of the arrow, as shown in Fig. 6. During this movement the crank 27 will traverse the slot 47 and will 45 oscillate the link 46 upon the bar 43 as a pivot. This will remove the hook 49 from engagement in the hole 38 in the element 37, and the parts are so arranged that such disengagement of the hook is accomplished at about the same time as the other end of 50 the slot 47 is reached by the operating crank 27. As soon as this releasing takes place the springs 32 will act to snap the switch open insuring a quick break. The slot 47 provides a lost motion device so that the 55 opening movement of the switch contacts cannot be hindered by the operator after he has once placed the apparatus in condition for switch opening.

60 The configuration of the retaining means and link mechanism is such that the switch

contacts 29 move continuously in direction in both opening and closing, there being no retrograde movement.

Referring now to the modified form of switch structure shown in Figs. 7 and 8, it 70 will be apparent that I have shown a two pole externally operated enclosed switch associated with fuses as before.

The blades 29 are interconnected by a suitable crossarm comprising a metal rod 52 and two insulating sleeves 53, the sleeves being clamped to the blades by means of a suitable connecting device 54. Intermediate the sleeves I have mounted a washer 55 and a collar 56, the collar having a circumferential groove 57 therein. A link 58 is pivoted on the rod 52, the link 58 being provided at one end with a slot 59 to provide a lost motion device in cooperation with the switch operating crank 27. The insulating base 22' supports intermediate the fixed contacts 24 a retaining device which comprises a bifurcated post, one arm 60 of which is provided with an open notch 61 and with an outwardly bent lip 62. The other arm 63 of the post is of spring material flexible relative to the first arm 60, and has a lip 64 as shown.

The end of the link 58 opposite the slot 59 has a struck out shoulder portion 65, 95 which is adapted to be received within the notch 60 when the switch is in completely closed position, and to resist the effect of the spring which biases the switch toward the open position. This spring 66 is preferably coiled, as shown, and mounted on the insulating base 22' intermediate the pivot posts 25, one end of the spring being fastened at 67 and the other end 68 being engaged in the circumferential groove 57 of the collar 56. This spring tends to assume the position shown in Fig. 8, thereby keeping the contacts in open position, the spring being compressed when the switch is closed, as shown in Fig. 9.

100 The operation of this modified form of switch is similar to that of the modification previously described. Considering the switch in the open position shown in Fig. 8 and it is desired to close the switch, the 115 crank 27 will be moved clockwise to the position shown in Fig. 10. This will turn the link 58 upon the rod 52 until the crank 27 comes to the end of the slot 59. Further movement of the crank 27 will move the 120 movable contacts 29 downwardly and will move the shoulder 65 past the lip 62 on the post 60 until the parts assume the position shown in Fig. 11. Further movement will cause the spring arm 63 of the bifurcated post to move the shoulder portion 65 into engagement with the upper edge of the slot 61. When in this position, the spring 66 which tends to bias the contacts open, will be resisted by the engagement 125 130

of the shoulder and slot. The opening movement of the crank arm 27, as shown in Fig. 12, will turn the link 58 on the rod 52, thereby disengaging the shoulder 65 from the notch 61, and permitting the spring 66 to snap the switch open.

Referring now to the modified form of switch shown in Figs. 13 to 18, inclusive, it will be apparent that I have shown a two pole externally operated enclosed switch associated with fuses as before.

The movable contacts 29 are connected by a suitable crossarm which includes a metal rod 69 and suitable insulating sleeves 70 which are connected to the blades by any suitable connecting device 71. The insulating sleeves 70 are spaced from one another a suitable distance to accommodate four washers 72, a spring 73 intermediate the washers and a link mechanism 74. This link mechanism as shown comprises two substantially flat pieces of metal held together by rivets at 75. Each of these links is provided with a hooked shaped end 76 on the side of the rod 69 remote from the rivets 75. The two parts of the link mechanism 74 are pressed toward one another by the springs 73, so that the hooks are normally in engagement with one another when the switch is open, as shown in Fig. 13. Each member of the link 74 is provided near the riveted end 75 with a slot 76', and the operating crank 27 is adapted to cooperate with this slot. Springs 77 are wrapped around the operating crank near each of the side walls 26 of the enclosing casing 20. One end 78 of these springs is fastened preferably to the side wall 26 and the other end 79 is passed through a hole 40 near the end of the rod 69. These springs bias the switch contacts toward the open position.

On the insulating base 22" and intermediate the fixed contacts 24, I have mounted a rigid retainer or post 80 adapted to engage the hook shaped ends 76 of the link mechanism 74, and restrain the switch contacts from movement under influence of the springs 77 after the switch contacts have been moved to completely closed position. To provide for this the post 80 has two beveled faces 81 which diverge from a point 82 toward a pair of shoulders 83. Intermediate these shoulders is a web 84 which supports the upper part of the post. The outline of this post is clearly shown in the perspective view of Fig. 19, which view shows a three pole switch having the positive make quick break features shown in the 60 two pole form in Fig. 13.

The mode of operation of this embodiment of my invention is analogous to that of those previously described. When it is desired to close the switch in the position shown in Figure 14 the operating crank is

brought into engagement with the inner end of the slots 76', whereupon the movable contacts 29 are moved into engagement with the fixed contacts 24. During this movement the hook shaped ends 76 engage the surfaces 81 of post 80. As these surfaces are diverging the hooks 76 will be forced apart thereby compressing the springs 73. When the switch is in completely closed position, as shown in Fig. 15, the hooks 76 have been passed beyond the shoulders 83 and the spring 73 has snapped the hooks behind the shoulders so that the spring 77 cannot open the switch contacts. Reversal of the movement of the operating member 27 will permit the same to travel through the slot 76' and oscillate the link mechanism on the rod 69 as a pivot, as shown in Fig. 18, thereby freeing the hooks 76 from the shoulder 83 and permitting the springs 77 to snap the contacts open.

It will be noted that the springs 73 operate against the members of the link mechanism in such a way that they would assist the springs 77 in opening the switch were the switch not completely closed, and in some forms of switches where the quick break feature is not necessary, I may dispense with the springs 77, using the spring 73 to accomplish two functions—that is, the spring 73 may be used to latch the switch in completely closed position, and also to push the movable contacts free of the fixed contacts, if the movable contacts are not completely closed.

In the three embodiments shown in the drawings, I have illustrated enclosed knife blade switches with an operating crank pivoted in the walls of the enclosure in alignment with the pivotal mounting of the knife blades. It is, however, to be understood that this is not a necessary part of my invention, for the device may be used in exposed switches and in switches of other than the knife blade type, also the switch operating crank may be pivoted at a distance remote from the pivotal mounting of the knife blades for each type of switches used, and this displacement of the pivotal mounting of the operating crank will merely change the contour of the link mechanism and retaining means.

It is further to be noted that the forms of embodiments illustrated show structures in which the opening and closing forces on the switch blades are balanced on account of the symmetrical mounting of the blades, biasing springs and link mechanisms, and that the contacts move continuously in direction in either opening or closing.

I claim:

1. In a switch, stationary and movable contacts, a crosshead carrying said movable contacts, an operator, lost motion means connecting said operator and said crosshead,

and means for interposing resistance to the closing movement of said operator by obstructing the movement of said lost motion means.

5 2. In a switch, stationary and movable contacts, a crosshead carrying said movable contacts, an operator, means loosely associating said operator and said crosshead, and means for interposing resistance to the 10 closing movement of said operator by obstructing the movement of said lost motion means and for thereafter positively latching said movable contacts in extreme closed position, said loose association contributing

15 to the unlocking of said latching when said operator is moved in a switch opening direction.

3. In a switch, stationary and movable contacts, a crosshead carrying said movable contacts, an operator, pivotally mounted means connecting said operator and said crosshead, means for interposing resistance to the closing movement of said operator by obstructing the movement of said lost motion means, and for thereafter positively latching said movable contacts in extreme closed position, and means associated with said pivotally mounted means for positively unlatching said movable contacts when said 30 operator is moved in a switch opening direction.

4. In a switch, stationary and movable contacts, a crosshead for said movable contacts, an operating member for said switch, means connecting said operator and crosshead, said means being pivotally movable with respect to said crosshead and having a lost motion connection with said operator, and latching means to hold said movable contacts in closed position, said last named means being engaged as said pivotally movable means pivots about said crosshead.

5. In a switch, stationary and movable contacts, the movable contacts being biased to open position, a crosshead carrying said movable contacts, an operating crank for closing and opening said switch, a member mounted on said crosshead and slidably connected to said crank member, engageable means on one end of said member, and means for engaging said engageable means, only after a complete closure of the movable contacts.

6. In a switch, stationary and movable contacts, the movable contacts being biased to open position, a crosshead carrying said movable contacts, and means opposing the biasing action and locking said contacts closed only after the same have been completely closed, said means comprising a link movably mounted on said crosshead, means for engaging and latching the end of said link which is adjacent the crosshead, and an operator loosely connected to said link

to swing the same into and out of engagement with said latching means.

7. In combination, a switch having a plurality of fixed and movable contacts, a crossarm rigidly connected to the movable contacts and insulated therefrom, means biasing said movable contacts to the open position, a link mechanism carried by the crossarm, a retainer cooperative with said link mechanism to oppose said biasing means, and a switch operating means to close said switch and set up such opposition and to open said switch by disengaging said mechanism from said retainer. 75

8. In combination, a switch having a plurality of fixed and movable contacts, a crossarm rigidly connected to the movable contacts and insulated therefrom, means cooperating with said crossarm to bias said movable contacts to the open position, a link mechanism pivotally carried by the crossarm, a retainer cooperative with said link mechanism to oppose said biasing means, and a switch operating means to close said switch and set up such opposition and to open said switch by disengaging said mechanism from said retainer, said biasing means exerting substantially the same force on each of the movable contacts on opening of the switch. 95

9. In combination, a switch having a plurality of fixed and movable contacts, a crossarm rigidly connected to the movable contacts and insulated therefrom, means biasing said movable contacts to the open position, a link mechanism carried by the crossarm, a retainer cooperative with said link mechanism to oppose said biasing means, and a switch operating means cooperative with said crossarm to close said switch and set up such opposition and to open said switch by disengaging said mechanism from said retainer, said operating means being arranged to exert substantially the same force on each of the movable contacts in closing the switch. 100 110

10. In combination, a switch having a plurality of fixed and movable contacts, a crossarm rigidly connected to the movable contacts and insulated therefrom, means biasing said movable contacts to the open position, a slotted link mechanism pivotally carried by the crossarm, a retainer cooperative with said link mechanism to oppose said biasing means, and a switch operating means cooperating with said link mechanism and crossarm to move said contacts to close said switch and set up such opposition and to open said switch by rocking said mechanism on the crossarm to disengage said mechanism from said retainer, said mechanism being slotted to permit quick break. 115 125

11. The combination with an electric switch having fixed and movable contacts, 130

- 6
said contacts being biased to open position, and an operating means for said movable contacts, of means for insuring complete closure of said movable contacts, said means comprising a link pivotally mounted relative to said movable contacts and a fixed retainer, one of the aforesaid parts of said insuring means being yieldable to permit relative movement of said parts only in one direction in a single path whereby they may function, said operating means and link interengaging during the opening movement of the operating means to oscillate the link and disable said insuring means, said relative movement being in a different path.
12. The combination with an electric switch having fixed and movable contacts, said contacts being biased to open position, and an operating means for said movable contacts, of means for insuring complete closure of said movable contacts, said means comprising a link pivotally mounted relative to said movable contacts and a fixed retainer, one of the aforesaid parts of said insuring means being yieldable to permit relative movement of said parts only in one direction in a single path whereby they may function, said operating means and link interengaging during the opening movement of said operating means through a lost motion connection to oscillate the latter and disable said insuring means, said relative movement being in a different path whereby the opening movement of the movable contacts is sharp.
13. In combination, an electrical switch having a plurality of fixed and movable contacts, said contacts being biased to open position, a crossarm rigidly connected to said movable contacts and insulated therefrom, a crank, a link pivoted on said crossarm and slidingly connected with said crank, said link being provided with a hook on the side thereof opposite said crank, and means adapted to engage and retain said hook when the switch is completely closed.
14. In combination, an electrical switch having a plurality of fixed and pivotally mounted contacts, said pivotally mounted contacts being biased to open position, a crossarm rigidly connected to said pivotally mounted contacts and insulated therefrom, a pivoted crank, a link pivoted on said crossarm and slidingly connected with said crank, said link being provided with a hook on the side thereof opposite said crank, and means adapted to engage and retain the hook when the switch is completely closed, the opening movement of the pivoted crank rocking said link on said crossarm to disengage the hooked end of the link from the last mentioned means.
15. In a switch, stationary contacts, movable contacts, means for applying closing pressure to bring said contacts into engage-

ment comprising a link engaging said movable contacts and pivotally mounted with respect thereto, and means for interposing resistance to said closing movement just as said engagement begins, said means changing from an obstructing to an engaging relation with said switch closing means upon an increase in said closing pressure and the swinging of said link about its pivotal mounting.

16. In a switch, stationary contacts, movable contacts, means for closing said contacts into engagement comprising a link engaging said movable contacts and pivotally mounted with respect thereto, and means for interposing resistance to said closing movement just as said engagement begins and for engaging said switch closing means after said closing engagement is substantially completed.

17. The combination with an electric switch having fixed and movable contacts, said contacts being biased to open position and operating means for said movable contacts, of means for insuring complete closure of said movable contacts said means comprising a hooked link pivotally mounted relative to said movable contacts, and a pivotally mounted biased element having an opening therein and cooperative with the hooked link whereby movement of the link in one direction may displace the element against its biasing to permit the hook to enter said opening, the biasing returning the element to its normal position and engaging the hook.

18. The combination with an electric switch having fixed and movable contacts, said contacts being biased to open position and operating means for said movable contacts of means for insuring complete closure of said movable contacts, said means comprising a hooked link pivotally mounted relative to said movable contacts, and a pivotally mounted biased element having an opening therein and cooperative with the hooked link whereby movement of the link in one direction may displace the element against its biasing to permit the hook to enter said opening, the biasing returning the element to its normal position and engaging the hook, said operating means being connected to said link through a lost motion device, whereby the link may be oscillated to remove the hook from its cooperative element thereby permitting the first named biasing means to function.

19. In a knife blade switch having a knife blade mounted pivotally on a post and means fastening said post in fixed position, the combination therewith of a spring to bias said blade to one position and a mounting device for said spring, said mounting device comprising a substantially flat sheet of metal having outwardly and upwardly

extending prongs to engage the spring, said device being held in place by the fastening means for the pivot post.

20. The combination of a switch having a fixed and movable contact of means of insuring complete closure of the switch said means comprising a first fixed part and a second part movable with the movable contact, one of said parts including a spring pressed element, the other part carrying an element cooperating with the spring pressed element to remove the movable contact from the fixed contact, the other of said parts further including a positive locking

15 shoulder cooperative with the spring pressed element to positively hold the switch closed.

21. In a mechanism for positive make quick break switches, a link having at one end a hook, and at the other end an elongated slot, and provided near the first end with an aperture.

22. In an electric switch having a plurality of movable contacts, a metallic cross-arm, insulating sleeves, connecting devices to clamp such sleeves in spaced relation on the crossarm and to support the movable contacts, and a link mechanism mounted on the crossarm intermediate the sleeves, said mechanism including a member hooked at

30 one end and slotted at the other.

23. In an electric switch having a plurality of movable contacts, a metallic cross-arm, insulating sleeves, connecting devices to clamp such sleeves in spaced relation on the crossarm and to support the movable contacts, a link mechanism mounted on the crossarm intermediate the sleeves, said mechanism including a member hooked at

35 one end and slotted at the other, and means

associated with the link mechanism where- 40 by the movable contacts are manually operable in one direction.

24. In an electric switch having a plurality of movable contacts, a metallic cross-arm, insulating sleeves, connecting devices 45 to clamp such sleeves in spaced relation on the crossarm and to support the movable contacts, a link mechanism mounted on the crossarm intermediate the sleeves, said mechanism including a member hooked at 50 one end and slotted at the other, and means whereby the movable contacts are urged in one direction.

25. In an electric switch having a plurality of movable contacts, a metallic cross-arm, insulating sleeves, connecting devices to clamp such sleeves in spaced relation on the crossarm and to support the movable contacts, a link mechanism mounted on the crossarm intermediate the sleeves, said 55 mechanism including a member hooked at one end and slotted at the other, means whereby the movable contacts are urged in one direction, and means cooperating with said hooked end to oppose said urging 60 means only when the movable contacts are in an extreme position.

26. In a switch, stationary contacts, movable contacts, an operator, a link pivotally mounted with respect to said movable contacts and having a lost motion connection with said operator, means for insuring the complete closure of said movable contacts, comprising a spring adapted to be engaged by said link only when the movable contacts are pressed home with an appreciable force.

ALBERT P. BALL.
